ROCK DRILLING MECHANISM

Filed June 6, 1932

UNITED STATES PATENT OFFICE

WILLIAM A. SMITH, SR., OF EASTON, PENNSYLVANIA, AND WILLIAM A. SMITH, JR., OF PHILLIPSBURG, NEW JERSEY, ASSIGNEES TO INGERSOLL-RAND COMPANY, OF JERSEY CITY, NEW JERSEY, A CORPORATION OF NEW JERSEY

ROCK DRILLING MECHANISM

Application filed June 6, 1932. Serial No. 615,525.

This invention relates to rock drilling mechanism, but more particularly to a feeding device for rock drills of the fluid actuated type.

5 One object of the invention is to maintain a uniform feeding pressure on the working implement actuated by the rock drill.

Another object is to facilitate the withdrawal of the rock drill from the work after 10 the drill hole has been completed.

Still another object is to enable the rock drill to be manually rotated through the feeding device and by a handle arranged at the rear end thereof.

15 Other objects will be in part obvious and in part pointed out hereinafter.

In the accompanying drawing illustrating the invention and in which similar reference characters refer to similar parts,

20 Figure 1 is a longitudinal side view of a rock drill drilling mechanism constructed in accordance with the practice of the invention and having a supporting device which is shown partly broken away,

25 Figure 2 is a transverse view through the feeding device taken through Figure 1 on the line 2—2 looking in the direction indicated by the arrows, and

Figure 3 is a transverse view taken through 30 Figure 2 on the line 3—3.

Referring more particularly to the drawing, the drilling mechanism which is designated, in general, by A, comprises a percussive element or motor B, as for instance a 35 coal pick, adapted to actuate a working implement C for drilling holes in the rock D.

In accordance with the practice of the invention the motor B is provided with a feeding device adapted to be actuated by pressure 40 fluid for advancing the motor in the direction of the material D in accordance with the penetration of the working implement C thereinto and for effecting a reverse movement of the motor. The means provided for this purpose

45 comprises a feeding cylinder E wherein is a piston chamber F for the accommodation of a reciprocating piston G having a piston rod H which is fixedly connected to the motor B by means of a connection J. The connection J 50 may, as indicated, also serve as the back head

for the motor B and may be threaded to the rod H and to the motor B and be clamped to these elements by means of pinch bolts K.

Suitable closures are provided for the ends of the cylinder E in the form of heads L and O which may be threadedly connected to the ends of the cylinder. The head L which is arranged on the end of the cylinder E adjacent the motor B has a bore P to guide the rod H, and within the head L is a cavity Q for the reception of packing consisting of alternately arranged cup leathers R and metallic rings S to seal the front end of the piston E. A supply conduit T is connected to the head L for constantly admitting pressure fluid into the front end of the cylinder E to act against a front pressure area U of the piston G.

The head O on the rear end of the cylinder E is bored to form a series of stepped portions V, W and X of progressively increasing diameter in the order named from the outer or rear end of the head O. Disposed within the portion V of the bore is a spindle Y having a head Z which lies within the portion W of the bore and bears against a shoulder b at the juncture of the portions V and W. The spindle Y projects beyond the free end of the head O and into a bore c of a handle d which is clamped to the spindle by means of a nut e threaded on the end of the spindle.

The spindle Y is freely rotatable within the head O and has connected thereto a bar f preferably of rectangular shape which extends through a correspondingly shaped bore g in the piston G, thereby interlockingly engaging the piston for imparting rotary movement of the handle d to the motor B. Within the handle d is a chamber h to which pressure fluid is supplied by a conduit j connected to the handle.

From the chamber h, and in the handle d, leads a supply passage k which opens into a passage o in the spindle for conveying pressure fluid into a passage p which extends longitudinally through the bar f and communicates at its front end with the interior of the rod H. The bar f is, moreover, provided with a port q adjacent the head Z for exposing a rear pressure area r on the piston G to pres-

sure fluid for driving the piston forwardly through the cylinder E.

At the juncture of the chamber h and the passage k is a valve seat s for the accommodation 5 of a throttle valve t which is normally held closed by a spring u in the chamber h. The throttle valve t has a stem v which extends through the spindle and into a depression or notch w in the handle d wherein is 10 arranged a lever x whereby the throttle valve t may be opened.

Any suitable means, as for instance that 15 designated by y, may be provided for supporting the drilling mechanism. The means illustrated comprises a supporting frame z whereon is arranged a column 2 to support a saddle 3. Preferably the saddle 3 is provided 20 with a bore 4 for the reception of a rotatable member 5 having a clamp element 6 adapted to be secured to the cylinder E to support the weight of the drilling mechanism.

The operation of the device is as follows: 25 Let it be assumed that the pressure area U on the piston G is exposed to pressure fluid and in which case, of course, in the absence of pressure fluid in the rear end of the cylinder E the piston G will be held in the rear extremity of the piston chamber F. If then the throttle valve t is opened pressure fluid 30 flows through the passages k, o and p into the rod H, thence into the back head J for distribution to the motor by suitable valve mechanism (not shown) for actuating the working implement C into the material D.

35 Upon the admission of pressure fluid into the passage p a portion of such pressure fluid flows through the port q into the rear end of the piston chamber F to act against the pressure area r of the piston G and drive the piston 40 ton, and therefore the motor B, in the direction of the material D. This movement of the piston and the motor and the operation of the motor B will continue as long as the throttle valve t remains open or until the piston 45 ton G reaches the forward extremity of the piston chamber F.

Upon releasing the lever x the valve t will be closed by the spring u thus cutting off the further admission of pressure fluid into the 50 channels communicating with the passage k. The pressure fluid remaining in these passages will then pass through the motor B thereby evacuating the interior of the rod H and the associated passages. When this 55 pressure fluid has been sufficiently reduced in value the pressure fluid acting against the

front pressure area U of the piston G will immediately retract the piston G and the motor B.

In order to constantly shift the position 70 of the cutting bit of the working implement during the drilling operation the handle d may be rotated or oscillated and, inasmuch as the handle d is interlockingly connected to the piston G by the bar f, the piston and the motor B will follow the movement of the handle d. In this way the working implement C, which is of course also slidably interlocked 75 with the motor B in a well known manner, will be rotated or oscillated to change its position with respect to the work. 80

We claim:

1. In a drilling mechanism, a fluid actuated motor adapted to actuate a working implement, a feeding cylinder, a fluid actuated piston therein and having opposed pressure areas, a rod on the piston supporting the motor and being hollow to convey pressure fluid to the motor, a support for the feeding cylinder, a handle, a spindle for the handle rotatable in the cylinder and having a bore, 85 a bar affixed to the shaft slidably interlocked with the piston and having a passage extending longitudinally therethrough for conveying pressure fluid from the bore to the rod, means in the handle for selectively supplying pressure fluid through the passage to one pressure area and to the rod, a port in the bar to convey pressure fluid from the passage to one pressure area, and means for constantly supplying pressure fluid to the other pressure 90 area. 95

2. In a drilling mechanism, a fluid actuated motor adapted to actuate a working implement, a feeding cylinder, a piston in the cylinder, a rod on the piston affixed to the motor and being hollow to convey pressure fluid to the motor, a handle rotatably connected to the feeding cylinder, a bar on the handle slidably interlocked with the piston and having a passage therethrough communicating with the rod and with one end of the cylinder, means for constantly supplying pressure fluid to one end of the piston, and means for selectively supplying pressure fluid to the other end of the piston and to the motor. 105 110 115

In testimony whereof we have signed this specification.
